UNITED STATES PATENT OFFICE.

WILLIAM P. McCLOSKEY, OF PITTSBURG, PENNSYLVANIA.

FERRULE VALVE AND TUBE CLEANING DEVICE.

986,844.

Specification of Letters Patent. Patented Mar. 14, 1911.

Application filed November 10, 1910. Serial No. 591,704.

To all whom it may concern:

Be it known that I, WILLIAM P. McCLOSKEY, a citizen of the United States of America, residing at Pittsburgh, in the county of Allegheny and State of Pennsylvania, have invented certain new and useful Improvements in Ferrule Valve and Tube Cleaning Devices, of which the following is a specification, reference being had therein to the accompanying drawing.

This invention relates to a ferrule valve and tube cleaning device, and the object of the invention is to provide simple and effective means in a manner as will be herein-after set forth for cleaning valves and tubes containing water, steam, or other matter under pressure.

My invention aims to provide a cleaning device that can be advantageously used for cleansing valves and cocks of water mains, without necessitating the shutting off of the pressure of water within the main and without removing the valve or cock. To this end, I have devised a cleansing device that is strong and durable, inexpensive to manufacture, easy to install, and efficient for the purposes for which it is intended.

The invention will be hereinafter specifically described and then claimed and reference will now be had to the drawing, wherein:

Figure 1 is a side elevation of the cleaning device, and Fig. 2 is a vertical sectional view of the same.

1 denotes a water main and tapped into this main is the lower threaded end 2 of a cock 3, said cock having a tapering plug 4 provided with a port 5. The upper end of the cock 3 is threaded, as at 6, and screwed upon the upper end of said cock is the lower enlarged end 7 of a barrel 8, said barrel having the upper end thereof reduced to provide a nipple 9 and the walls of this nipple are exteriorly screw threaded.

10 denotes a rod extending through the nipple 9 into the barrel 8, the lower end of the rod being spiral shaped, as at 11, and intermediate the ends of said rod and at the upper end of the spiral 11 is a head 12. Detachably mounted upon the upper end of the rod 10 is a suitable handle 13 whereby said rod can be easily manipulated.

Screwed upon the nipple 9 is the depending annular flange 14 of a cap 15 and this cap has the opening 16 thereof enlarged to provide an annular groove or seat 17 for a

conical shaped gasket 18, preferably made of rubber. The gasket 18 is adapted to movably support the rod 10, whereby said rod can be adjusted longitudinally of the barrel 8 and can be slightly vibrated or rocked within said barrel.

It is a well-known fact that the port 5 of a cock often becomes clogged with sediment and other matter and to cleanse the same, it is only necessary to close the cock 3 by rotating the plug 4 a quarter of a revolution. If a pipe is connected to the upper end of the cock it can be easily removed and the barrel 8 placed in position. The plug 4 can then be rotated to place the port 5 in longitudinal alinement with the barrel 8. The spiral end of the rod 10 can then be pushed into the port 5 and moved back and forth therein or rocked gradually to get the sediment and other matter from the port 5. The gasket 18 permits of the rod 10 being freely moved while the water is under pressure within the barrel 8, and it is the pressure of water that assists in removing the sediment or incrustations on the walls of the port 5 after it is loosened by the spiral 11 of the rod 10. After the port 5 has been cleansed the rod 10 can be pulled upwardly, the cock 3 closed, the barrel 8 removed and connections made with the upper end of the cock.

The device in its entirety can be made of light and durable metal and of various sizes according to its use, and while in the drawings there is illustrated a preferred embodiment of the invention, it is to be understood that the structural elements are susceptible to such changes as fall within the scope of the appended claims.

What I claim, is:

A valve and tube cleaning device comprising a relatively long cylindrical barrel provided at one end with an offset internally-threaded annular flange for detachably connecting the barrel to a valve casing, said barrel having its upper end reduced to provide a vertically disposed nipple, the latter having peripheral threads, said nipple disposed axially with respect to the body of the barrel and communicating therewith, a cap provided with a depending annular flange formed with interior threads for engagement with the peripheral threads of the nipple, said cap formed with a centrally disposed opening, said opening gradually increasing in diameter inwardly, the flange of

said cap having the upper portion of said threads cut away to provide a continuation of the enlarged part of the opening through the cap, a resilient gasket seated in the opening of the cap and in the cut away portion of the flange of the cap and abutting against the upper edge of said nipple, a rod extending through said gasket and nipple and depending in said barrel, that portion of the rod within the barrel being in the form of a spiral, a head abutting against the upper terminus of the spiral portion of said rod, a handle detachably connected to the rod, and the inner diameter of said nipple being materially greater than the diameter of said rod. 15

In testimony whereof I affix my signature in the presence of two witnesses.

WILLIAM P. McCLOSKEY.
